UNITED STATES PATENT OFFICE.

CHARLES V. SWANSON, OF VELVA, NORTH DAKOTA.

VENTILATOR.

Application filed May 12, 1923. Serial No. 628,650.

To all whom it may concern:

Be it known that I, CHARLES V. SWANSON, a citizen of the United States, residing at Velva, in the county of McHenry and State of North Dakota, have invented certain new and useful Improvements in Ventilators, of which the following is a specification.

My invention relates to ventilators and the object is to provide an efficient and easily operated device the use of which will provide proper circulation of air in a room or rooms of a building. The device is particularly adapted for admitting outside atmosphere without opening the regular windows of a building and is so constructed as to admit such air without a direct draft.

In the accompanying drawings:

Fig. 1 is an outside elevation of a portion of a wall having a window frame embodying my improvements.

Fig. 2 is a right hand side elevation or edge view of Fig. 1, showing portions of the wall above and below the window frame.

Fig. 3 is an enlarged sectional elevation on line 3—3 in Fig. 1.

Fig. 4 is an inside elevation of a window frame embodying my improvements.

Fig. 5 is an enlarged sectional elevation as on line 5—5 in Fig. 4.

Referring to the drawing by reference numerals, 5 is the wall of a building, 6 are the outside casings, 7 the inside casings, 8 the lintel, 9 the sill and 10—11 the upper and lower sash of a window, and 12 are the parting strips for the sash. 13 are the vertical wall members between the inner and outer casings.

My device is mounted in a housing above the regular lintel 8 and formed by extending the casings and walls 13 above said lintel the casings, walls 13 and the lintel 8 forming three sides of said housing, the fourth or top side of it being formed of horizontal members 6^a—7^a of the casings secured to a secondary lintel 14 spaced above lintel 8 a predetermined distance, preferably about 10 inches. The housing is in effect a rectangular vent opening above a regular window. In said opening I mount in vertical spaced relation a series of light skeleton frames of which 15 is a detachable outer frame normally in place about flush with the outside casing 6 and held by means such as turn buttons 17 on the casing (see Figs. 1 and 3). Said frame is

covered by a light, fine-mesh wire netting 18. Next to said frame 15 and within the vent I place another frame 19 in which is secured a number of horizontally disposed, parallel, bars 20 of suitable flat material and placed at an angle with relation to the lintel. These bars act as baffle plates or deflectors to change the direction of air currents coming through netting 18. This frame may be held in place between the outer frame 15 and parting strips 21 within the housing (see Fig. 3).

In Fig. 3 I have shown two vertically disposed frames 22 within the housing and behind frame 21, each having a suitable cloth 23 stretched on it, and said frame being suitably secured either permanently as with nails 24 or removably held by any suitable means (not shown).

The inner opening of the vent frame or housing is normally closed by a shutter consisting of a plurality of horizontally arranged wings 25 hinged at their opposite ends on pins 26 bearing in the vertical walls 13. Two of said pins are shown for the two wings 25 in Fig. 5 as extended through the wall 13 and provided each with a rocker arm 27, said arms being connected by a link 28 and the upper one having an eye 28^a engaged by the upper end of a vertically arranged tension spring 29 the lower end of which is secured as at 30 in the wall 13 in a manner to keep the spring in tension at all times. Above said rocker arms 27 I mount a sheave 31 on a pin 32. A cable 33 is suitably secured as at 34 to the upper rocker arm, passed over the sheave 31 thence downwardly and connected to the upper end of a rod 35 the lower end of which is secured to a collar 36 on a stud 37 projecting horizontally through a vertical slot 38 in the casing member 7. Said slot may be protected by a slotted metal plate 39 secured on the casing, the protruding end of the stud being provided with a thumb screw 40 which may be used to hold the stud at any elevation in the slot. It will be readily understood that when the thumb screw is loosened the spring 29 pulls the rocker arms down thereby normally holding the shutter wings or blades 25 in vertical position.

By pulling the thumb screw and its stud 37 toward the bottom of the slot the bight of the cable 33 connected to the rocker arms 27 pulls them upwardly and thereby swings the shutter blades away from

the frame and permits outside atmosphere to enter a room in which the device is installed. This outside air circulates through the device, first going through the fine-mesh screen 18, then deflected inwardly and upwardly on the plates 20, thence through the cloths 23 and into the room over the blades 25. Any moisture or fine snow which may possibly be forced through the fine-mesh screen 18 will be deflected outwardly again on the sloping blades 20. The inner cloths 23 will break the force of any wind which may get through screen 18 so that all the air which finally circulates into the room over the tops of blades 25 circulates gently within the room without any discomfort to the occupants. Sufficient fresh air for all ordinary purposes may thus be admitted and the amount of it is easily regulated without opening the window itself.

In Fig. 5 7^b is a removable part of the casing 7 which may be secured to the casing in any suitable manner, as with screws 7^c, or removed when access to the sheave 31 and adjacent parts is desired.

What I claim is:

A ventilator consisting of a frame formed integral with a window frame and above the movable sash of said window, and means mounted in said frame and the window frame for controlling the passage of air through said ventilator frame, said means

in the ventilator frame comprising an outer screen, a frame with baffle plates and adjacent said outer screen, a plurality of vertically disposed sheets of fabric mounted inwardly from said baffle plates and a shutter consisting of a plurality of hinged blades mounted within the ventilator frame adjacent its inward opening and normally closing said opening, said means for controlling the passage of air consisting of rocker arms secured on the adjacent pivots of the shutter blades, a link connecting said rocker arms, a tension spring connected to one of said rocker arms and to the window frame to normally hold the rocker arms down and the shutter blades in closed position, and means for opening the shutter against the tension of said spring, said opening means consisting of a sheave rotatably mounted in the ventilator frame above and adjacent the said rocker arms, a cord attached to said rocker arms and adapted to be passed upwardly therefrom over the sheave, thence downwardly within the window frame, a vertically slidable securing means for holding the lower end of said cord at any desired position for the purpose described.

In testimony whereof I affix my signature.

CHARLES V. SWANSON.
